UNITED STATES PATENT OFFICE

1,998,341

BLIND STITCH SEWING MACHINE

Alfons Strobel, Munich, Germany

Application September 20, 1930, Serial No. 483,315
In Germany September 24, 1929

2 Claims. (Cl. 112—178)

The invention relates to blind stitch sewing machines in which the work is supported under the stitch plate by a saddle and is pressed against the sides of the saddle by benders.

The object of the invention is to enable machines of this kind to be easily adjusted for sewing cloths of different thicknesses.

For this purpose the benders are, according to the invention, carried by levers abutting against springs having adjustable holders, so that the position of the benders in relation to the saddle can be adjusted by adjusting the spring holders.

An embodiment of the invention is shown in the accompanying drawing, in which

Fig. 1 is an elevation of the relevant parts of a sewing machine,

Fig. 2 a section on the line A—B thereof, and
Fig. 3 a section on the line C—D of Fig. 1.

The stitch plate 19 is carried by a yoke 1a, and below the same, at the sides of the saddle 8, there are benders 2, 3, in this example bevelled rolls of rigid or elastic material carried by double armed levers 4 having pivots 5 and engaging into guide brackets 6. The upper arm of each of these levers engages into a guide 9 of U-section, in which it abuts against a coiled spring 10 tending to hold it against one of the limbs of the guide. The guide 9 is adjustable lengthwise of a slot 11 in the yoke 1a, the guide having a stud 12, into which is screwed a screw 13, which can be turned by means of a button 14. By this means the benders 2 and 3 can easily be adjusted in relation to the

saddle 8, without affecting the compression of the springs 10.

The work fed over the saddle lies under the slot in the stitch plate 19, and a pivoted bender, indicated by broken lines at 24 in Fig. 2, is for each stitch rocked so that it presses the cloth through the slot into the path of the needle. In this respect the mechanism is similar to mechanism shown for the same purpose in the specification of my Patent No. 1,828,789, and illustrated therein in Figs. 4, 5, 6 and 9.

The lateral benders 2, 3 ensure that the work lies smoothly on the saddle and is presented to the needle without rucks or creasing.

What I claim as my invention and desire to secure by Letters Patent of the United States is:—

1. A blind stitch sewing machine having in combination with a stitch plate and a work saddle thereunder, two levers separately pivoted at opposite sides of said saddle, springs against which said levers abut, adjustable holders for said springs, and work benders carried by said levers.

2. A blind stitch sewing machine having in combination with a stitch plate and a work saddle thereunder, two levers separately pivoted at opposite sides of said saddle, springs against which said levers abut, a yoke supporting said stitch plate, adjustable holders for said springs carried by said yoke, and work benders carried by said levers.
